CLOSURE

Peter Vassallo, Avalon, N. J.

Application January 13, 1940, Serial No. 313,795

2 Claims. (Cl. 312—147)

This invention appertains to new and useful improvements in closures and more particularly to the closure illustrated in my Patent No. 2,142,464, issued January 3, 1939, and improvements thereon.

The principal object of the present invention is to provide a closure especially adapted for refrigerators which can be readily opened and closed at will with a minimum loss of cold air from the interior of the refrigerator.

Another important object of the invention is to provide a closure especially adapted for refrigerators which involves doors of the sliding type which will remain in any desired open position pending removal of what is desired from the refrigerator.

Still another important object of the invention is to provide closure means which will conserve space in that no excess space is required for the opening and closing thereof.

These and various other important objects and advantages of the invention will become apparent to the reader of the following specification.

In the drawings:

Figure 1 represents a front elevational view of a refrigerator equipped with the improved closure.

Figure 2 is a vertical sectional view taken substantially on the line 2—2 of Figure 1.

Figure 3 is a rear elevational view of one of the doors.

Figure 4 is a section on the line 4—4 of Figure 1.

Figure 5 is a fragmentary detailed sectional view taken substantially on the line 5—5 of Figure 1.

Referring to the drawings wherein like numerals designate like parts, it can be seen in the drawings that the invention is incorporated in a refrigerator structure which is generally referred to by numeral 5. The improved closure structure is generally referred to by numeral 6 and, of course, is mounted in the front wall 7 of the refrigerator.

The front wall 7 has a plurality of door openings 8, 9, 10 and 11. In each of these door openings a door 12 is disposed, and, of course, as is clearly shown in Figures 1 and 2, a portion of the wall is left between each of these openings and will hereinafter be referred to as the divider 13. The uppermost divider 13 will have a groover 14 therein for receiving the lower portion of the uppermost door 12. This defines a rest for the upper door 12, which when elevated by its handle 15 can be lifted into the narrow

pocket 16 in the portion of the wall 7 above the door openings.

The underlying door 17 and the door 18 will be construed as the outside doors and the doors 12 and 19 as the inside doors. The door 17 operates through a slot 20 in the overlying divider 13 and is capable of resting in the groove 14 of the underlying divider 13 as is shown in Figure 2 and as do the doors 19 and 18. In other words, each divider serves as a guide for one door and as a rest for the other door. The front wall 7 has guide grooves therein at the door openings 8, 9, 10 and 11 denoted by numeral 21 to guide the doors. Shelves 22 extend inwardly of the refrigerator from each divider 13 and from the stoop 23.

As shown in Figure 3, each of the doors consists of a frame *a* in which is mounted a window pane *b*.

Each vertical edge portion of the door is rabbed as at 24 to accommodate a bowed spring 25. Each of these springs is formed with a slot 26 in each end thereof through which a screw 27 is disposed, this screw passing through a washer 28, the latter bearing against the spring. Obviously, these springs wipe the side walls of the grooves 21 and the inside of the pocket 16, as well as the slots 20, to the end that the doors can be held in practically any desired elevated position while articles are being removed from the shelves 22.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a cabinet, an enclosure having a plurality of vertically arranged and closely spaced openings in one wall thereof, shelves in the enclosure vertically spaced and each being on a horizontal plane with the portion of said wall between two openings, said portions between the openings defining dividers, closures vertically slidable in the openings, each of said dividers having a slot therein through which an underlying closure can be moved, each of said dividers also being formed with a groove for receiving the overlying closure edge.

2. In a cabinet, an enclosure having a plurality of vertically arranged and closely spaced openings in one wall thereof, shelves in the enclosure vertically spaced and each being on a horizontal plane with the portion of said wall be-

tween two openings, said portions between the openings defining dividers, closures vertically slideable in the openings, each of said dividers having a slot therein through which an underlying closure can be moved, each of said dividers also being formed with a groove for receiving the overlying closure edge, the vertical edges of the walls at the openings being formed with guide

5 grooves, one side of each of the closures adjacent each vertical edge portion thereof being formed with a channel, a curved strip spring in each of the channels, each of the springs having its end portions slotted and a retaining element disposed through each of the slots and into the closure.

PETER VASSALLO.
